UNITED STATES PATENT OFFICE

ARTHUR J. FAUSEK AND IRWING F. FAUSEK, OF CLAYTON, MISSOURI

CUTTING MACHINE

Application filed July 24, 1930. Serial No. 470,395.

This invention relates generally to metal cutting machines and more specifically to a cutting machine of the type adapted for use in guiding gas-burning cutting torches during cutting operations thereof, the predominant object of the invention being to construct a machine of this type which is of such improved construction and arrangement that very efficient results are obtained in the use thereof.

Figure 1 is a plan view of our improved cutting machine.

Figure 2 is a fragmentary vertical section through the machine illustrated in Figure 1.

Figure 3 is a cross-section of the machine illustrated in Figures 1 and 2.

Figure 4 is a cross-section on line 4-4 of Figure 1.

Figure 5 is a view similar to Figure 2 but showing the fragment of the machine illustrated in elevation.

In the drawings, wherein is shown for the purpose of illustration, merely, one embodiment of the invention, A designates our improved cutting machine generally. The cutting machine A includes a pair of supporting elements 1 and 2 which are located at opposite ends of the machine, these supporting elements being shaped as shown clearly in Figure 4 and being each provided with a pair of horizontally aligned apertures 3. Extended longitudinally of the machine A from the supporting element 1 to the supporting element 2 is a pair of guiding members 4 and 5, said guiding members being substantially square in cross section and being arranged on edge as shown clearly in Figures 3 and 4; that is to say, the arrangement of the guiding members is such that the diagonal diameters thereof are in upright and transverse planes. At their opposite ends the guiding members are provided with reduced portions 6 which are extended through the apertures 3 formed in the oppositely disposed supporting elements, the shoulders 7 at the point of junction be-

tween the guiding members proper and the reduced end portions thereof serving to maintain the spaced relation of said supporting elements. The outer end portions of the reduced portions 6 of the guiding members are screw-threaded and nuts 8 are screwed on said reduced end portions in a manner to securely fix the guiding members to the supporting elements. The guiding members are properly positioned and maintained in their proper positions by plates 5^a which are located at the supporting elements 1 and 2, said plates being interposed between the shoulders 7 on the guiding members 4 and 5 and the supporting elements 1 and 2 and being provided with extensions 5^b which are inclined and contact with faces of said guiding members.

Extended longitudinally of the machine A is a screw 9 which is provided with reduced end portions 10 extended through apertures formed through the oppositely disposed supporting elements 1 and 2. At the extreme outer ends of the reduced opposite end portions of the screw 9 a pair of hand operating wheels 11 are fixedly secured to said reduced end portions whereby the screw may be conveniently subjected to rotary movement in the bearings provided by the apertures in the supporting elements 1 and 2.

C designates a movable carriage which includes a substantially horizontal plate 12. The plate 12 is provided with a downward extended lug 13 which is located at one side thereof, and a similar lug 14 which is located at the opposite side of said plate (Fig. 2). Supported by the lug 13 is a horizontal trunnion 15 which rotatably supports a roller 16. The roller 16 is provided with a substantially V-shaped, annular groove which receives the upper portion of the guiding member 4, and said roller 16 is confined between a head portion 17 at the inner end of the trunnion 15 and a nut 18' screwed on the outer end of said trunnion so that said roller is pre-

vented from moving longitudinally of the trunnion.

Extended through an opening formed through the lug 14 is a bolt 18. This bolt 5 rotatably supports a roller 19 having a V-shaped, annular groove which receives the upper portion of the guiding member 4, and, as in the case of the roller 16, said roller 19 is mounted on said bolt so that it is incapable of substantial movement longitudinally thereof. Pivotally supported at one of its ends by the bolt 18 is an arm 20 (Figure 2), said arm being extended approximately parallel with respect to the screw 9 and being 10 spaced from said screw in an upward direction. The arm 20 is provided with a downwardly extended partial nut which is provided with a semicylindrical opening through which the screw 9 passes, said semicylindrical opening being provided with arcuate extensions 22 which are extended into the depression between portions of the thread of the screw. 23 designates an expansible coil spring which is seated at its opposite ends in cavities formed in the plate 12 and arm 20 respectively, and said coil spring tends to force the free end of the arm 20 downwardly so as to maintain the nut 21 in engagement with the screw 9.

Projected downwardly from the plate 12 of the carriage C is a pair of oppositely disposed arms 24 and 25 which are connected together at their lower ends by a plate 25' which extends transversely of the machine. 20 Extended outwardly from the upper portion of the arm 24 is a trunnion 26 (Figure 3) on which a roller 27 is rotatably mounted. The roller 27 is provided with a V-shaped circumferential groove which receives the upper portion of the guiding member 5, and said roller is capable of movement longitudinally of the trunnion 26. The arms 24 and 25 are located in a vertical plane which is intermediate the vertical planes in which the lugs 13 and 14 are located and, therefore, the roller 27 which is supported by the arm 24 is disposed in like relation with respect to the rollers 16 and 19 supported by said lugs 13 and 14. In other words, the upper rollers 16, 19, and 27, are disposed in horizontal triangular arrangement whereby three point support for the carriage is obtained.

Extended downwardly from the plate 25' is a pin 28 which is screw-threaded at its lower end. This pin extends through an aperture 29 formed through the upper portion of a bar 30 which extends transversely of the machine as illustrated in Figure 2 and said aperture is provided with an enlarged lower portion 31. Screwed on the lower screwthreaded end of the pin 28 is a wing nut 32 and arranged on the pin 28 immediately above said wing nut is a washer 33. Interposed between the washer 33 and the top wall 60 of the enlarged portion 31 of the aperture 29 is a coil spring 34. The washer 33 is of slightly less diameter than the enlarged portion of the aperture 29, hence, the bar 30 is yieldingly attached to the pin 28.

35 designates a pair of arms which are extended outwardly in opposite directions from the bar 30 at one end thereof. These arms support a pair of rollers 36 and 37 which are provided with V-shaped circumferential grooves and are rotatably supported on pins 38 extended outwardly from said arms, said rollers being capable of movement longitudinally of their supporting pins. The upper portions of the V-shaped circumferential grooves of the rollers 36 and 37 receive the lower edge of the guiding member 4 as shown in Figures 2 and 3. Rotatably supported on a pin 39 which extends outwardly from the end of the bar 30 opposite to the end thereof at which the rollers 36 and 37 are located is a roller 40, said roller being provided with a circumferential V-shaped groove which receives the lower edge portion of the guiding member 5 and being capable of movement longitudinally of the pin 39 by which it is supported. As is the case with the upper rollers 16, 19, and 27, the lower rollers 36, 37, and 40 are disposed in horizontal, triangular arrangement whereby three point contact between the lower rollers and the guiding members is obtained.

Supported upon the top face of the plate 12 of the carriage C is a supporting member 41 which includes a pair of spaced, upstanding arms 42. The lower portion of the supporting member 41 is in the form of a substantially circular plate 43 which is rotatably connected to the plate 12 by a centrally located pin 44. The pin 44 is screwthreaded at its lower portion and this screwthreaded portion is screwed into a screwthreaded opening in the plate 12 (Figure 2), and at its upper end the pin 44 is associated with an operating wheel 45, the lower face of which contacts with the top face of the plate 43. The operating wheel 45 may be rotated reversely to move the lower face thereof out of contact with the plate 43 whereupon the supporting member 41 may be rotated about the pin 44 to any desired adjustment, and when the desired adjustment has been attained the operating wheel may be screwed downwardly to clamp the supporting member in position. To assist in the proper adjustment of the supporting member the edge of the plate 43 thereof is provided with an indicating mark 46 (Figure 3) and the top face of the plate 12 is provided with graduations 47 (Figure 1) with respect to which said indicating mark 46 is moved when the supporting member 41 is rotated about the pin 44.

Formed in the upstanding arms 42 of the supporting member 41 are pairs of horizontally aligned apertures through which a pair of rods 48 is extended. These rods 48 are 130

arranged in horizontal alinement and at the forward ends thereof are joined by a bar 49 which is securely fixed to the rods by nuts 50 screwed on screwthreaded reduced end 5 portions of said rods. The opposite ends of the rods 48 are joined by a similar bar 51 which is connected to said rods by nuts 52, said bar 51 being provided with an aperture 53 which receives the lower end of an upstanding rod 54 in a manner to fixedly secure said rod 54 to said bar 51. 55 designates a screw which is extended through apertures 56 one or both of which are screwthreaded, said screw being provided with reduced end 15 portions having smooth surfaces which are arranged for rotation in apertures formed in the bars 49 and 51. Fixed to the outer end of the screw 55 is an operating handle 57 which facilitates rotation of the screw. 20 58 designates a head which is provided with an opening formed therethrough through which the upstanding rod 54 extends, and 59 designates a set screw which rigidly connects said head to said rod. The head is provided with a second opening 60 which is disposed at an approximate right angle to the direction of extension of the opening 59 and a rod 61 is extended through this last mentioned opening, said rod being fixed in position by a set screw 61'. At one end thereof the rod 61 just referred to is provided with a split collar comprised of arcuate elements 62 and 63 which are secured together by bolts or other suitable fastening devices 64'. The 35 split collar embraces a cutting torch T of suitable construction in a manner to cause said torch to be rigidly fixed to the rod 61.

The cutting torch T is supplied with gas by a plurality of flexible conductors 64, 65, and 66, which are connected to the tail piece of the torch as shown in Figures 1 and 3, and valves 67 are arranged at said tail piece for controlling the flow of gas to the torch from said conductors. Mounted on a plate 68 supported by the upstanding arms 42 of the supporting member 41 is a plurality of valves 69, 70, and 71. These valves are of ordinary construction and the flexible conductors 64, 65, and 66 are connected thereto; that is to say, the flexible conductor 64 is connected to the valve 69, the flexible conductor 65 is connected to the valve 70, and the flexible conductor 66 is connected to the valve 71. The valve 71 is connected by a conductor 72 to a 55 fuel gas supply, while the valves 70 and 69 are connected by conductors 73 and 74 to an oxygen supply. The valves 69 and 70 which control the passage of acetylene to the torch and of oxygen to preheating flames of said 60 torch, are simultaneously operable by a single operating handle 75 pivoted at 76 to a fixed part of the valve structure, while the valve 71 which controls oxygen leading to the cutting jet of the torch is operable by an independent operating handle 77 pivoted at 78,

and each of said operating handles is provided with suitable means 79 for maintaining same in a depressed position.

To prevent the flexible conductors 64, 65, and 66 from becoming tangled during operation of the machine, we provide an open ring 80 (Figure 3) through which said flexible conductors are extended. This ring is provided with a downwardly extended tubular extension 81 which is arranged in telescoping arrangement with the upper portion of the rod 54 and is provided with a set screw 82 which provides for fixing said open ring at various elevations.

It is essential in using our improved cutting machine that the machine be in a substantially level position and, therefore, we provide the supporting elements 1 and 2 with auxiliary feet 83 which are adjustable vertically. We also attach wedges 84 to said supporting elements by means of flexible connectors 85 and these wedges may be introduced beneath the feet of the supporting elements 1 and 2 to assist in leveling the machine.

In the use of our improved cutting machine, said machine is supported on the metal plate or other element to be cut, this plate having been marked to indicate the lines on which same is to be cut. The torch T is then arranged at the proper elevation and is fixed at such elevation by tightening the bolts 64' of the split collar which embraces said torch, after which the torch may be moved to the proper transverse point so as to bring it above the line to be cut by rotating the screw 55 associated with the supporting member 41. When the torch has been properly set as described and has been located at the starting point of the cut the screw 9 will be rotated with the result that the carriage C will be caused to travel longitudinally of said screw and as the torch T moves with the carriage said torch which, of course, has been previously placed in operation, will cut the element being operated on along the line it travels.

When it is desired to cut the element being operated on along an arc of a circle the supporting member 41 may be rotated about the pin 44 and because of the presence of the indicating mark 46 and the graduations 47 accurate cutting of this sort may be accomplished. When the carriage has reached the end of a cutting operation it is not necessary to return same by reversing the direction of rotation of the screw 9. Instead the carriage may be quickly returned to the starting position by elevating the outer end of the arm 20 against the action of the coil spring 23 so as to free the nut 21 from the screw 9 whereby free movement of the carriage with respect to the screw is possible.

An important feature of the invention resides in the fact that the upper rollers 16 and 19 are the only rollers which are held against

movement longitudinally of the pins by which they are rotatably supported. All of the other rollers may move longitudinally of their supporting pins, hence, if the guiding members 4 and 5 should be bent out of their true line the loosely mounted rollers will shift along their supporting pins and thereby avoid a binding action between the rollers and the guiding members. Also because three point contact is obtained between the carriage C and the guiding members 4 and 5 the carriage is more likely to be maintained in a level position. Finally our improved cutting machine includes valves for controlling the passage of gas to the torch which are located on the carriage of the machine. This is a decided advantage inasmuch as the valves are located in the most convenient position, and furthermore as the valves on the carriage of the machine are auxiliary to the valves 67 at the tail of the torch, the last mentioned valves may be set to obtain a cutting flame having the desired characteristics and this setting of said valves need not be disturbed when use of the torch is temporarily discontinued, the flame of the torch being controlled entirely by operation of the auxiliary valves.

Due to the fact that the torch T is supported by the rod 61 which is capable of axial rotation within the opening 60 in the head 58, the torch may be locked, by the set screw 61', in a position where it is extended at an angle to the true vertical for bevel cutting.

35. We claim:

1. A cutting machine comprising supporting means, guiding members supported by said supporting means, a traveling carriage supported by and movable along said guiding members, means associated with said carriage for engaging a cutting torch, screw-threaded means for imparting movement to a part associated with said carriage, and a manually releasable element associated with said carriage and movable into and out of cooperative engagement with said screw-threaded means.

2. A cutting machine comprising supporting means, guiding members supported by said supporting means, a traveling carriage supported by and movable along said guiding members, means associated with said carriage for engaging a cutting torch, screw-threaded means for imparting movement to a part associated with said carriage, and a manually releasable element associated with said carriage and movable into and out of cooperative engagement with said screw-threaded means, the last mentioned means comprising a pivoted arm, and a partial nut on said pivoted arm adapted to engage said screwthreaded means.

3. A cutting machine comprising supporting means, guiding members supported by said supporting means, a traveling carriage,

means associated with said carriage for engaging a cutting torch, and rollers associated with said carriage and movable along said guiding members, said rollers being so located as to provide three point contact between the carriage and the guiding members

4. A cutting machine comprising supporting means, guiding members supported by said supporting means, a traveling carriage, means associated with said carriage for engaging a cutting torch, and rollers associated with said carriage and movable along said guiding members, said rollers being arranged in horizontal triangular formation so as to provide three point contact between the carriage and the guiding members.

5. A cutting machine comprising supporting means, guiding members supported by said supporting means, said guiding members comprising bars rectangular in cross section arranged with their diagonal diameters extended in vertical and horizontal planes, a traveling carriage, means associated with said carriage for engaging a cutting torch, and rollers associated with said carriage and movable along said guiding members, said rollers being provided with annular grooves shaped to receive edge portions of said guiding members and being so located as to provide three point contact between said carriage and said guiding members.

6. A cutting machine comprising supporting means, guiding members supported by said supporting means, said guiding members comprising bars rectangular in cross section arranged with their diagonal diameters extended in vertical and horizontal planes, a traveling carriage, means associated with said carriage for engaging a cutting torch, and rollers associated with said carriage and movable along said guiding members, said rollers being provided with annular V-shaped grooves to receive edge portions of said guiding members and being so located as to provide three point contact between said carriage and said guiding members.

7. A cutting machine comprising supporting means, guiding members supported by said supporting means, a traveling carriage, means associated with said carriage for engaging a cutting torch, upper rollers associated with said carriage and movable along the upper portion of said guiding member, and lower rollers associated with said carriage and movable along the lower portion of said guiding members.

8. A cutting machine comprising supporting means, guiding members supported by said supporting means, a traveling carriage, means associated with said carriage for engaging a cutting torch, upper rollers associated with said carriage and movable along the upper portion of said guiding member, lower rollers associated with said carriage

- and movable along the lower portion of said guiding members, and means for yieldingly connecting said lower rollers to said carriage.
- 5 9. A cutting machine comprising supporting means, guiding members supported by said supporting means, a traveling carriage, means associated with said carriage for engaging a cutting torch, upper rollers associated with said carriage and movable along the upper portion of said guiding member, lower rollers associated with said carriage and movable along the lower portion of said guiding members, and means including a 10 spring for yieldingly connecting said lower rollers to said carriage.
- 10 10. A cutting machine comprising supporting means, guiding members supported by said supporting means, a traveling carriage, means associated with said traveling carriage for engaging a cutting torch, and rollers associated with said carriage, said rollers being provided with circumferential grooves which receive said guiding members 15 and one of said rollers being so supported as to be capable only of rotary movement while others of said rollers are mounted so as to be capable of rotary movement and movement longitudinally of their axes.
- 20 11. A cutting machine comprising supporting means, guiding members supported by said supporting means, a traveling carriage, means associated with said traveling carriage for engaging a cutting torch, and 25 rollers associated with said carriage, said rollers being provided with circumferential grooves which receive said guiding members and being so located as to provide three point contact between said carriage and said guiding members, one of said rollers being so supported as to be capable only of rotary movement while others of said rollers are mounted so as to be capable of rotary movement and movement longitudinally of their axes.
- 30 12. A cutting machine comprising supporting means, guiding members supported by said supporting means, a traveling carriage, means associated with said traveling carriage for engaging a cutting torch, and 35 rollers associated with said carriage, said rollers including a set of upper rollers movable along the upper portions of said guiding members and a set of lower rollers movable along the lower portions of said guiding members, said rollers being provided with circumferential grooves which receive portions of said guiding members and certain of said rollers being so supported as to be capable only of rotary movement while others 40 of said rollers are mounted so as to be capable of rotary movement and movement longitudinally of their axes, the rollers of each set of rollers being so located as to provide three point contact between said carriage and said guiding members.
- 45 13. A cutting machine comprising supporting means, guiding members supported by said supporting means, a traveling carriage, means associated with said traveling carriage for engaging a cutting torch, rollers associated with said carriage, said rollers including a set of upper rollers movable along the upper portions of said guiding members and a set of lower rollers movable along the lower portions of said guiding members, said rollers being provided with circumferential grooves which receive portions of said guiding members and certain of said rollers being so supported as to be capable only of rotary movement while others of said rollers are mounted so as to be capable of rotary movement and movement longitudinally of their axes, the rollers of each set of rollers being so located as to provide three point contact between said carriage and said guiding members.
- 50 14. A cutting machine comprising supporting means, guiding members supported by said supporting means, a traveling carriage supported by and movable along said guiding members, means rotatably mounted on said carriage for supporting a cutting torch, screw-threaded means for imparting movement to a part associated with said carriage, and a manually releasable element associated with said carriage and movable into and out of cooperative engagement with said screw-threaded means.
- 55 15. A cutting machine comprising supporting means, guiding members supported by said supporting means, a traveling carriage supported by and movable along said guiding members, means mounted on said carriage for supporting a cutting torch, the last mentioned means including traveling means for moving said cutting torch in a straight line, screw-threaded means for imparting movement to a part associated with said carriage, and a manually releasable element associated with said carriage and movable into and out of cooperative engagement with said screw-threaded means.
- 60 16. A cutting machine comprising supporting means, guiding members supported by said supporting means, a traveling carriage supported by and movable along said guiding members, means rotatably mounted on said carriage for supporting a cutting torch, the last mentioned means including traveling means for moving said cutting torch in a straight line, screw-threaded means for imparting movement to a part associated with said carriage, and a manually releasable element associated with said carriage and movable into and out of cooperative engagement with said screw-threaded means.
- 65 17. A cutting machine comprising supporting means, guiding members supported by said supporting means, a traveling car-

riage supported by and movable along said guiding members, means associated with said carriage for engaging a cutting torch, screw-threaded means for imparting movement to said carriage, a single valve for controlling passage of both fuel gas and preheating oxygen to the torch, and a second valve for controlling passage of oxygen to the cutting jet of the torch.

19 In testimony whereof we have hereunto set our hands.

ARTHUR J. FAUSEK.
